(57) **CLAIM**

The ornamental design for a red light therapy pod as shown and described.

DESCRIPTION

FIG. 1 is a perspective view of a red light therapy pod showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an embodiment in which the red light therapy pod is in a partially folded status thereof; and,

FIG. 10 is an enlarged view of area **10** shown in FIG. 1. The dash-dot-dash broken lines define the bounds of the enlargement and form no part of the claimed design.

1 Claim, 10 Drawing Sheets
